Primary Examiner — Robin V Webster*(74) Attorney, Agent, or Firm* — Muncy, Geissler, Olds & Lowe, P.C.**CLAIM**

The ornamental design for a flowing water sterilization module, as shown and described.

DESCRIPTION

FIG. 1 is a top, left perspective view of a flowing water sterilization module showing our new design;

FIG. 2 is a bottom, left perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof; and,

FIG. 8 is a bottom plan view thereof.

The broken line showing is for the purpose of illustrating portions of the flowing water sterilization module which form no part of the claimed design.
